EGG BEATER

Filed April 13, 1929

INVENTOR.
CHARLES E. KAIL.

BY *Philip S. Johnson*
ATTORNEY.

UNITED STATES PATENT OFFICE

CHARLES E. KAIL, OF BINGHAMTON, NEW YORK, ASSIGNOR TO A & J MANUFACTURING COMPANY, OF BINGHAMTON, NEW YORK

EGG BEATER

Application filed April 13, 1929. Serial No. 354,896.

My invention relates to an egg beater construction and has for its primary object the provision of a simple, inexpensive, and easily assembled egg beater structure having many detailed advantages and improvements over the art, each of which constitutes an object of the invention.

This application is a continuation in part of my former application, Serial No. 140,595 filed October 9, 1926, for an egg beater.

One of the objects of my invention consists in the provision of a novel handle securing means for the egg beater.

Another object comprises a simple and novel means for securing the rotatable driving gear to its shaft.

A further and important object lies in the provision of novel means for securing the ends of the gear frame and the beater frame together.

Still another object lies in the provision of novel means for securing the guard plate to the beater frame.

Another object lies in a novel securing means between the lower end of the beater frame and the supporting loop for the guide plate.

Referring now to the figures of the accompanying drawings forming a part of this application and wherein like reference numerals indicate like parts, the detailed construction of these various elements and parts will be described.

Figure 1 is a side elevation of an egg beater constructed in accordance with my invention, certain parts being shown in section for clearness.

Figure 2 is a detail sectional view taken on the line 2-2 of Figure 1.

Figure 3 is a detail sectional view illustrating the means for securing the driving gear to its shaft.

Figure 4 is a detail side view partly in section illustrating the means for securing the free ends of the gear frame and beater frame together and for securing the guard plate to the beater frame.

Figure 5 is a detail bottom view illustrating the means for connecting the beater frame and the guard supporting loop.

In carrying out my invention, I provide what I have termed a gear frame 1 comprising a pair of flat strips of metal secured together at their upper ends as at 2 and having their remaining portions turned outwardly from each other as at 3 to provide the parallel spaced legs 4 and 5 which serve to support the driving gear 6. This may consist of a flat disk provided with peripheral teeth extending alternately on opposite sides of the disk. Hollow bearings 7 are provided in suitable aligned openings in the legs 4 and 5 of the gear frame and are adapted to rotatably support a shaft 8 provided at one end with a gear handle 9. Secured upon the shaft 8 between the legs 4 and 5 is a sleeve 10 which carries the driving gear 6. The shaft 8 is provided with a notch or recess 11 into which may be forced, as by crimping or otherwise, a portion of the material of the sleeve 10, as at 12 whereby the sleeve 10 is securely and rigidly locked upon the shaft 8. Obviously, therefore, rotation of the shaft 8 by means of the handle 9 will rotate the driving gear 6.

The extreme lower ends of the frame leg portions 4 and 5 are bent to provide substantially circular sockets 13 adapted to receive and embrace the upper ends 14 of a wire beater frame consisting of a looped wire 15, the lower closed end 16 of which is formed angular with respect to the loop whereby to form supports for and limit the downward movement of beater blades 17 rotatable on the beater frame 15. The lower ends of the beater blades, which are of the usual loop construction, are provided with the usual suitable openings through which the beater frame 15 passes and permitting rotation of the blades thereon. The upper ends of the blades 17 are bent at right angles as at 18 and secured together for rotation about the legs of the beater frame. These upper ends of the beater blades carry pinions 19 so disposed as to bring the teeth thereof into mesh with the teeth of the driving gear 6 whereby upon rotation of such driving gear, the beater blades 17 will rotate freely on the beater frame 15.

A guard plate 20 is provided for the pin-

ions 19 and consists of a saddle member as shown in Figure 1 provided with lateral flanges or extensions 21 having openings through which the upper ends 14 of the beater frame are adapted to pass. This guard plate 20 may be driven over the upper ends of the beater frame and in order to secure the same rigidly to such ends, the ends 14 are provided with a swaged or other suitably formed lug 10 or key 22 over which the flanges 21 of the guard plate are driven. Thus, the guard plate is rigidly secured to the upper ends of the beater frame 15 at a point below and independent of the gear frame 4, the lower formed ends 13 of such gear frame being disposed directly above the guard plate.

It will be clear from Figure 1 that the upper ends 14 of the beater frame are provided with notches 23 into which are crimped or otherwise forced a portion of the material of the formed ends 13 of the gear frame 4 as shown clearly at 24. Thus the upper ends of the beater frame and the lower ends of the gear frame are securely and rigidly held together.

A supporting or stabilizing loop 25 is provided and has its upper ends secured as at 26 to the depending portions of the guard plate 20 and its lower looped portion 27 secured to the angular lower end of the beater frame 15 as shown clearly in Figures 1 and 5. At the point of engagement between these two elements, it will be noted that the wire beater frame is flattened as at 28 to receive the flat loop portion of the supporting member 25, which member has adjacent the flattened portion 28 and on opposite sides thereof a pair of tongues 29 struck from the material of the supporting loop and bent over into securing engagement with the flat portion 28. Thus these members are rigidly secured together.

Suitably secured in the upper end of the gear frame 1 and extending on opposite sides thereof is a pin 30 provided with swaged or otherwise suitably formed keyways or lugs 31. A handle member 32 preferably of wood is driven onto each projecting end of this pin 30 thereby forming a handle or grip portion for the egg beater, portions of the handle being secured to the pin 30 by a close driving fit and of course prevented from rotating on the pin by the lugs 31.

Of course, changes may be made in details of construction and arrangement of parts without departing from the spirit and scope of my invention. I do not limit myself, therefore, to the exact structure herein shown and described, other than by the appended claims.

I claim:

1. An egg beater comprising a beater frame and a gear frame secured together, bearings in said gear frame, a shaft rotatable in said bearings and a sleeve on said shaft

carrying a driving gear, said shaft having a notch into which is crimped a portion of the metal of said sleeve whereby said sleeve and shaft are secured for rotation together.

2. An egg beater comprising a wire beater frame and a flat metal gear frame secured together, beater elements rotatably journaled on said beater frame and carrying pinions, a driving gear in said gear frame meshing with said pinions, a guard plate secured to one end of said beater frame, and a looped supporting member secured at its upper ends to said guard plate and at its lower looped end to said beater frame, said beater frame being flattened at the point of engagement therewith, and tongues struck from said supporting members and engaging said flattened portion.

In testimony whereof, I affix my signature.

CHARLES E. KAIL.
